UNITED STATES PATENT OFFICE.

THOMAS J. WHITNEY, OF PHILADELPHIA, PENNSYLVANIA.

DESIGN FOR A COMB-CASE.

SPECIFICATION forming part of Design No. 21,456, dated April 12, 1892.

Application filed March 14, 1892. Serial No. 424,897. Term of patent 7 years.

To all whom it may concern:

Be it known that I, THOMAS J. WHITNEY, a citizen of the United States, and a resident of Philadelphia, Pennsylvania, have invented a new and original Design for a Comb-Case, of which the following is a specification.

My design is fully shown in the accompanying drawing, which represents a perspective view of the comb-case.

- 10 The leading features of the design are the back A, having an arched top B and tapering receptacle C secured to the back and the projecting tray D at the base, minor features of the ornamentation being the ribbed band *a*
- 15 on the front and ends of said tray, the paneled bottom *b* of the same, the rope-like edge

c of the front and ends, the representation of scales or shingles on the back A, the beaded edge *d* of the arched top B, and the representation of sheaves of wheat at *f* on either *20* side of the arched top.

I claim--

The design for a comb-case, substantially as described, and as shown in the accompanying drawing.

In testimony whereof I have signed my name to this specification in the presence of two subscribing witnesses.

THOMAS J. WHITNEY.

Witnesses:

JNO. E. PARKER,
HARRY SMITH.
